FRIEDRICH WILHELM LEFELMANN, OF AUE, GERMANY.

PROCESS FOR THE PRODUCTION OF COKE FROM WOOD-TAR.

1,064,350.

Specification of Letters Patent. Patented June 10, 1913.

Application filed October 1, 1912. Serial No. 723,366.

To all whom it may concern:

Be it known that I, FRIEDRICH WILHELM LEFELMANN, chemist, a subject of the German Emperor, residing at Aue, Westphalia, Germany, have invented a new and useful Process for the Production of Coke from Wood-Tar, in Particular from Tar Made of Wood of Deciduous Trees; and I do hereby declare the following to be a full, clear, and exact description of the same.

The present invention relates to a process for the production of soft and hard coke from wood tar and the recovery of the by-products.

15 The utilization of tar obtained from the wood of deciduous trees has hitherto been attended by considerable difficulties and in consequence thereof the only use to which such tar was put was that as a fuel. It was 20 hitherto impossible to completely distil this tar, as at the commencement of the coking process the wood tar would rise in the distillation chamber and choke the coolers and pipes so that it was impossible to produce 25 hard coke.

According to the present invention the tar from deciduous tree wood is utilized in such a manner, that first the lighter distillation products and the heavy oils are removed by 30 a fractionated distillation, whereupon the coking process proper is performed separately, the charge being automatically conveyed from the retort in which distillation takes place into a separate coking retort. 35 The volume of the pitch which remains in the distilling retort after fractionated distillation increases to about the fourfold when the temperature rises above about 250° centigrade, and this is employed to convey 40 the pitch from the distillation into the coking retort.

It is already known to produce coke from tar by rendering the tar thinly liquid by heating without any previous distillation 45 and then introducing it into a retort heated to white-heat. The previous heating of the tar has the sole object of rendering it more liquid.

With the present invention the main object is the removal of the more easily volatile components and the heavy oils and then the automatic conveying of the tar into the coking retort by the utilization of the spontaneous rising of the pitch. By such divi-

sion of the process it is obtained, that the attendance of the plant is considerably simplified, the danger of the tar boiling over is greatly reduced and choking and a danger of explosion are entirely avoided. This is of the greater importance, as wood tar, and in particular such from the wood of deciduous trees is very difficult to treat owing to its tendency to boil over. The wood of all deciduous trees may be used, but beech wood is particularly suited for the process.

In the accompanying drawing a plant for carrying out the process according to the present invention is exemplified in a diagrammatical manner. The process is performed in the following manner in this plant.

From the tar storage tank 1 the retort *a* is filled through the supply pipe 2 to a given height with tar and then heated over an open fire. The distillation gases will rise 75 to the condenser 4 whence the distillates may be separated in suitable manner into their various components. After the temperature has risen above 225° centigrade, the retort *a* is strongly heated so that the 80 pitch contained in it, which has a great tendency to boil over, will pass through the siphon 5, 6 into the retort *b* which has previously been heated to a high temperature. The branch 5 of the siphon 5, 6 projecting 85 into the retort *a* is preferably made glidable so that it may be lowered down to the bottom of the retort *a*. By such means the vessel *a* may be completely emptied by the action of this siphon. The pitch which 90 passes over into the highly heated retort *b* is there immediately exposed to a temperature of 400° centigrade and more and will therefore be coked without again foaming. The distillation gases pass into the condenser 7 and may there be separated in any 95 suitable manner. After the coking process has been completed, the retort *b* is opened and the coke is ejected, whereupon it is again filled from the retort *a*. The distillation gases may for instance be separated by means of the vessels 8, 9 and 10.

According to the present invention the heating of the tar is divided into a distillation process and the coking process proper; 105 the danger of explosions is avoided by the distillation being carried to a temperature of 225° centigrade only, while the coking

process proper takes place only after the greater part of the volatile gases has passed off.

I claim:

- 5 Process for producing coke from wood tar, in particular from tar made of the wood of deciduous trees, consisting in the tar being distilled to the passing over of the easily volatile distillation products and the heavy 10 oils, then being heated to a higher temperature until the tar rises by itself from the

distillation vessel into a closed coking retort, said coking retort being previously heated to the coking temperature.

In testimony whereof, I have signed my 15 name to this specification in the presence of two subscribing witnesses.

FRIEDRICH WILHELM LEFELMANN.
